Primary Examiner — Robert M. Spear*Assistant Examiner* — Kendra Leslie Hamilton(74) *Attorney, Agent, or Firm* — Quickpatents, LLC; Kevin Prince(57) **CLAIM**

I claim the ornamental design for a clip-on voice tag for a pet collar, as shown and described.

DESCRIPTION

FIG. 1 is a perspective view of a clip-on voice tag for a pet collar, showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right-side elevational view thereof; and,

FIG. 7 is a left-side elevational view thereof.

The broken lines showing a pet collar in FIG. 1 depict environmental matter and form no part of the claimed design.
